UNITED STATES PATENT OFFICE

2,525,064

MULTIPLE BELL CAP CLAMP

Benjamin L. Bragg, III, Fanwood, N. J., assignor
to Standard Oil Development Company, a corporation of Delaware

Application November 20, 1947, Serial No. 787,068

2 Claims. (Cl. 261—114)

1

The present invention relates to a means for securing bell or bubble cap elements in their operating relationship to the chimney elements in a fractionating tower plate. More particularly the invention relates to gang clamping means for such purpose, and especially to a clamp adapted for attachment and removal as a one-man operation.

In the use of fractionation equipment, to which the contemplated equipment specifically applies, it is customary for the bubble cap elements of each plate to be individually secured in their relationship to the plates, or to be secured by means of hold-down bars extended over several cap elements, or a row of such caps. The individual means employed usually consists of a bolt extended through the cap element to engage a yoke below the plate chimney. Such means require at least two operators, one above the plate and one below to secure or remove the cap elements for cleaning or other servicing operations. The hold-down bar arrangement tends to interfere with the flow of liquid across the plate, when operating the tower, and is therefore undesirable.

Since it is not uncommon for a fractionating tower to be equipped with plates containing 100 or more caps per plate, even small improvements in construction may result in considerable improvement in operating efficiency and saving of man power. It is an object of the invention to provide a means whereby bell or bubble caps may be attached and removed quickly and easily by one man. This and other features of the invention may be readily understood from the following specification when read in conjunction with the accompanying drawings, in which

Fig. 1 is a two plate vertical section through a portion of a fractionating tower.

Fig. 2 is an enlarged view of a single bell-type cap, showing the clamp in vertical section, and

Fig. 3 is a similar view showing the clamp in side elevation.

With reference to the drawings, the numeral 1 designates a fractionation tower provided with plate elements 2 having flanged openings or chimneys 3. Bell or bubble cap elements 4 are disposed over the chimneys 3 in the customary relationship, being spaced from the plates and from the chimney elements as by spacers 5.

Each bell cap 4 is provided with a hold-down rod member 6, having a hooked lower end dependent below the plate 2. The upper end of the rod 6 is secured concentrically of the cap by any suitable means, but preferably provision should be made to permit adjustment of the hooked lower end vertically with relation to the plate. As shown, the upper end of the rod passes through an opening in the cap, by threading or otherwise, and is secured by means of nuts 6a and 6b.

2

A hold-down bar member or gang type clamp 7 is provided to engage the hooked ends of a series of rod members 6. The opposite end portions of the bar 7 are formed with eye portions 7a, and adjusting bolts 8 are freely disposed therein. Each bolt 8 carries a cap nut 9 threaded on its upper end, providing a bearing for the upper end of a coil spring 10, the lower end of which bears against the upper end of the eye portion 7a on the bar clamp 7. The two springs associated with each clamp normally should exert a combined pressure against each clamp and maintain a minimum pressure therethrough on the hold-down rods 6, substantially equal to the gas pressure applied to the full area of the several bell caps in the series secured by the clamp. The resistance of the springs 10 may be adjusted as required, within the limitation imposed by the distance between the clamp 7 and the plate 2, by adjusting the position of the nuts 9 on the bolts 8.

It is contemplated that where required in order to balance or equalize pressure against the bar 7, as where a curved, circular, or otherwise deformed bar is found necessary, or where exceptionally heavy spring members are required to oppose gas pressure against the bubble caps associated with the bar clamp, additional eye pieces may be formed or attached to the bar 7 at spaced intervals to receive the bolts, caps nuts, and retaining springs for such purpose.

The dimensions of the several elements are critical only in so far as required for proper assembly of the clamp, and to avoid excessive interference with fluid flow below the plate. It is contemplated that ordinarily the clamp structure should not depend below the plate elements to a greater distance than the depth of the supporting structure of the plate as represented by the I-beam 11 shown in Fig. 2. With this distance designated as x , the other preferred dimensions, designated as a , b , and c , in the showing of Fig. 2 may be stated approximately as follows:

45

$$a+b=x$$

40

$$b=a+\frac{a}{2}$$

50

$$c=\frac{a}{2}$$

When fully extended, as shown in Fig. 3, the compressibility of the spring 10 should be approximately equal to

55

$$c+\frac{c}{2}$$

in order to permit the bar 7 to be removed from the hooked portions of the rods 6.

Although the invention has been described with reference to its application in conjunction with

fractionating and distillation equipment, it is not intended that it be considered as limited by such description for the purpose of illustration, but only by the appended claims, in which,

I claim:

1. In conjunction with a plate element having a plurality of fluid passageways therethrough, and cap elements for each of said passageways, a means for resiliently retaining said cap elements in vertical relation to said plate, comprising a hold-down rod member concentrically of each cap having a lower end dependent through said passageway below the plate, a clamping bar member engageable with the lower ends of a series of said rod members, bolt means freely supported by said bar member extensible vertically upward therefrom into endwise engagement with the lower surface of said plate, and expansion spring means between said bolt and bar adapted to extend the bolt upwardly, said bolt means when in engagement with the plate cooperating with said spring means to exert a resilient downward pressure against said bar resiliently resisting upward movement of the cap, rod and bar members.

2. In conjunction with a plate element having a plurality of fluid passageways therethrough and cap elements for each of said passageways, a means for resiliently retaining said cap elements

in vertical relation to said plate, comprising a hold-down rod member concentrically of each cap having a lower end dependent through said passageway below the plate, a clamping bar member engageable with the lower end of a series of said rod members, an eye portion at each end of said bar, a bolt member supported freely and vertically in each eye portion extensible upwardly therethrough, an adjustable cap nut on the upper end of said bolt, and an expansion coil spring member between said cap nut and eye portion, encircling said bolt.

BENJAMIN L. BRAGG, III.
